INGOT CASTING MOLD

John Gombosh, Pittsburgh, Pa.

Application July 13, 1948, Serial No. 38,470

9 Claims. (Cl. 22—147)

1

This invention relates to metal founding, and more particularly, to the casting of large metal bodies such as ingots where piping has heretofore been a detrimental factor.

This application is a continuation-in-part of an earlier or parent application, Serial No. 559,763, issued February 8, 1949, filed October 21, 1944, now Patent No. 2,461,052, for Method of Casting. The apparatus of this invention has features in common with the said earlier-filed application, and, as to such common features, this application is a continuation in part of the earlier application.

The parent application discloses a Method of Casting and mold apparatus designed to eliminate or materially reduce the formation of cavities or pipes in the casting of large metal bodies. As set forth in such application, the mold is formed with a peripheral trough at the upper portion of the mold cavity into which the molten material being cast may overflow, thereby removing dross and impurities from the casting. A separator plate is placed over the pour opening to the mold cavity and additional metal is added to cover the separator plate. The separator plate is mounted for vertical movement in the mouth of the cavity so that it may move downwardly and compensate for shrinkage of the metal in the mold cavity. In another embodiment of the invention shown in the said application, both the structure forming the peripheral trough and the separator plate are mounted for vertical movement with respect to the mold body. In both cases, compensation is provided for shrinkage of the metal within the mold cavity and such compensation is effective to reduce the detrimental effects due to the formation of pipes in the casting.

This invention relates generally to the structure of the mold by which compensation is provided for shrinkage within the mold cavity. More specifically, this invention is concerned with an arrangement by which the structure forming the peripheral trough about the pour opening to the mold cavity is mounted for movement to compensate for shrinkage of the metal within the mold cavity. In addition, this invention provides an improved separator plate structure for positioning over the pour opening of the mold cavity after such cavity has been filled to overflowing.

The invention may be more fully understood by reference to the accompanying drawings, in which:

Figure 1 is a vertical sectional view of an ingot mold having a trough structure in its upper end;

2

Figure 2 is a view similar to Figure 1 showing the mold cavity filled to overflowing and with a separator plate positioned over the trough structure;

Figure 3 is a partial vertical sectional view showing additional molten material poured over the separator plate;

Figure 4 is an enlarged plan view, part thereof being broken away, of the separator plate; and

Figure 5 is a sectional view taken substantially along the line V—V of Figure 4.

In the drawings, the numeral 1 designates a conventional ingot mold having a frusto-conical shaped trough structure 2 frictionally engaged with the sides of the mold adjacent the upper end thereof. The trough structure 2 is positioned at the upper end of the mold cavity 3 and provides a trough 4 into which dross and impurities floating on the molten metal in the cavity 3 may overflow through an opening 5 located centrally of the trough. The trough structure is provided with vertically depending flanges 6 which are placed in frictional engagement with the inner surfaces of the mold 1 for positioning the structure therein. Side members 7 extend angularly inwardly from the top edges of the flanges 6 and their terminal edges define the pour opening 5 which is rectangular in shape. The trough structure 2 comprises a central body portion 8 which is preferably formed of sheet metal and bent to give the structure 2 the desired contour. The sheet metal 8 is provided with a coating 9 of heat-resistant refractory material on its inner surface and a similar coating 10 on its outer surface. The sheet metal 8 imparts strength to the trough and the refractory coatings 9 and 10 enable it to withstand the intense heat of the molten metal.

When the trough structure 2 has been positioned in the mold as shown in Figure 1, the mold is ready for casting metal therein. The molten metal is introduced through the opening 5, or through the bottom if a bottom pour mold is used, and the cavity 3 is filled until it flows over the edges of the opening 5 into the trough 4. As pointed out above, the overflow carries with it dross and impurities floating on the surface of the molten metal. The overflow is continued until the trough is partially filled, it being preferred to stop the pouring before the level of the liquid in the trough approaches the edges of the opening 5.

After metal has overflowed into the trough 4, a separator plate 11 is placed in position over the opening 5 as shown in Figure 2. The plate 11 is a cover having a flat portion 12 and diverging

flanges 13 depending angularly from the edges of the top 12 for supporting engagement with the side members 7 of the trough structure 2. The separator plate 11 comprises a central body portion 14 preferably constructed from sheet metal and having an under coating 15 and an upper coating 16 of heat-resistant refractory material as best shown in Figure 4. The trough will have previously been filled with sufficient material that the lower edges of the flanges 13 will dip into such material. Movement of the lower edges of the flanges 13 into the molten metal in the trough 4 will chill the metal and a skin of solid metal will be formed between the flanges 13 and side members 7 which will be effective to hold the separator plate 11 in position on the trough structure 2.

After plate 11 is secure on the trough structure 2, additional molten material is poured into the top of the mold to cover the plate 11 as shown in Figure 3. In the preferred practice of the invention, the additional material poured on the top is molten metal and the top 12 is provided with a plurality of openings 17 as best shown in Figure 4. By providing the openings 17, metal may flow from above the plate 11 into the cavity 3 to fill voids therein due to contraction of the metal upon cooling. The openings 17 also provide vents through which hot gases may escape from the interior of the mold. In place of pouring metal into the space above the plate 11, the use of molten slag is contemplated.

It will be recalled that the trough structure 2 is initially held by friction within the mold 2. By mounting the structure 2 in this manner, the position of such structure may be adjusted vertically within the mold. This feature is very important when the action that takes place as the casting cools is considered. When the metal is poured, a shell is formed around the inner surface of the mold due to the particles of metal being cooled by the mold. This shell in its initial stages of formation is very hot and after a period of time will begin to cool as heat is dissipated through the mold. As the shell cools it will contract in a vertical direction and the frictional mounting of the structure 2 enables such structure to move downwardly with the shell as it contracts. In like manner, the material over the top or separator plate 11 will move down with the structure 2.

The use of the trough structure 2 and top 11 with the overlying layer of molten material will be found to materially reduce the formation of pipes in the casting within the mold 1. Various theories may be advanced to explain the improved results from the use of such structure. However, it is believed apparent that the use of the overlying layer of molten material prevents the premature hardening of the upper portion of the casting which is recognized to be one of the principal causes of pipe formations. In addition, the mounting of the separator plate 11 by which such plate may move vertically with respect to the mold provides compensation for the shrinkage of the metal in the mold. The body of material overlying the separator disc 11 is available to exert a downward pressure thereagainst.

After the casting has cooled and the mold is removed therefrom, the material above the plate 11 may be removed by a sledge hammer. After removal of such material, the structure 2 and separator plate 11 is removed from the casting if it does not pull off with the overlying structure.

While I have illustrated and described one 75

specific embodiment of my invention, it will be understood that this is merely by way of illustration and that various changes and modifications may be made within the contemplation of my invention and under the scope of the following claims.

I claim:

1. In an ingot casting mold, a member defining the upper end of a casting cavity in the mold and having a frictional fit with the sides of the mold so that it may move vertically with respect thereto, said member having an opening in the top thereof and parts cooperating with the sides of the mold to provide a trough extending around 10 said opening into which metal may overflow from said opening, and a cover for said opening for defining a space thereabove which is separated from the metal below said member and into which molten material may be poured to prevent premature hardening of the cast metal below said member.

2. The invention claimed in claim 1 wherein said member moves vertically downwardly with and in response to shrinkage of the metal within 20 said mold.

3. In an ingot casting mold, a member operating to define the upper end of a mold cavity within the mold, said member having flanges frictionally engageable with the inner surface of 30 the mold so that it may move vertically with respect thereto, said member having sides converging inwardly from said flanges and cooperating with the sides of the mold to define a trough extending around the inner surface of the mold, 35 said member having an opening centrally thereof through which molten metal may overflow from said cavity into said annular trough, and a cover for positioning over said opening to define a space above said member which is separated from the metal below said opening and into which molten material may be poured to prevent the formation 40 of pipe in the metal cast in said cavity.

4. The invention claimed in claim 3 wherein said cover is provided with diverging flanges having supporting engagement on said converging sides.

5. The invention claimed in claim 3 wherein said cover is constructed of sheet metal having a protective covering of heat-resistant refractory material on opposite surfaces thereof.

6. In metal casting apparatus, a mold having a bottom and vertical side walls defining the bottom and sides of a mold cavity in which metal is to be cast, a member positioned in said mold 55 and defining the top of said cavity, said member having vertically arranged flanges in frictional engagement with said side walls and side members projecting angularly inwardly from the top edges of said flanges to define a trough above said cavity and along said side walls, said side members having inner edges defining an opening centrally of said mold through which molten metal may overflow from said cavity into said trough, and a cover for closing said opening having flanges diverging angularly therefrom for supporting engagement on said side members, said diverging flanges being adapted to extend into the overflow metal in said trough and to be secured thereby to said side members, said cover and side members operating to define the bottom of a second cavity in said mold into which molten material may be poured to prevent the formation of a pipe in the casting in said first-named cavity.

7. Casting apparatus as claimed in claim 6

wherein said member and cover are formed from sheet metal and are provided with coatings of heat-resistant refractory material on opposite surfaces of the sheet metal.

8. In apparatus of the character described, a partition comprising a hollow truncated structure formed of sheet metal having upper edges defining an opening and lower edges defining a second opening of larger area than said first opening, said lower edges having side members depending vertically therefrom for frictional supporting engagement with the sides of a mold, the outer surface of said truncated structure defining the inner surface of a trough around a mold when said depending side members are in frictional supporting engagement with the sides of a mold, the sheet metal forming said truncated structure having opposite surfaces thereof provided with a protective coating of heat-resistant refractory material.

9. In apparatus of the character described, a partition comprising a hollow truncated structure having upper edges defining an opening and lower edges defining a second opening of larger area than said first opening, said lower edges having side members depending vertically therefrom for frictional supporting engagement with the sides

of a mold, and a cover having angularly diverging side members for supporting engagement with the outer surface of said truncated structure, said cover member providing a closure for said first opening when said diverging side members are supported on the outer surface of said truncated structure, said truncated structure and said cover member being formed from sheet metal having opposite surfaces thereof provided with a protective coating of heat-resistant refractory material.

JOHN GOMBOSH.
